UNITED STATES PATENT OFFICE.

ARTHUR TREVOR DAWSON AND GEORGE THOMAS BUCKHAM, OF LONDON, ENGLAND, ASSIGNORS TO THE VICKERS, SONS & MAXIM, LIMITED, OF SHEFFIELD, ENGLAND.

APPARATUS FOR RAISING CHARGES FOR BREECH-LOADING GUNS TO LOADING POSITION.

SPECIFICATION forming part of Letters Patent No. 633,816, dated September 26, 1899.

Application filed April 25, 1899. Serial No. 714,397. (No model.)

To all whom it may concern:

Be it known that we, ARTHUR TREVOR DAWSON and GEORGE THOMAS BUCKHAM, citizens of England, residing at No. 28 Victoria street, 5 Westminster, London, England, have invented certain new and useful Apparatus for Raising Charges for Breech - Loading Guns to Loading Position, (for which we have made application for a patent in Great Britain, No. 10 20,611, dated September 29, 1898,) of which the following is a specification.

This invention relates to apparatus applicable to a breech-loading gun, according to which the recoil of the gun compresses a spring 15 which on opening the breech for the purpose of loading the gun is released and automatically lifts the projectile or the explosive charge, or both, to a position in line with the bore, ready to be thrust into it by a rammer. 20 The accompanying drawings show apparatus according to this invention for the purpose.

Figure 1 is a side view of the cradle and rear part of a gun with the apparatus applied thereto. The other figures are drawn to an enlarged scale. Fig. 2 is an end view of the lifting-levers in their down position. Fig. 2^a is a detail transverse sectional view taken on the line 2^a 2^a, Fig. 2. Fig. 3 is a view similar to Fig. 2, showing the lifting-levers in their up position. Fig. 4 is a side view, partly in section, of the breech end of the gun and longitudinal section of the rear part of the spring; and Fig. 4^a is a longitudinal section 35 of the front part of the spring.

On the cradle *a* is fixed a cylindrical casing *b*, within which is fitted to slide a tube *c*, containing a helical spring *d*, the front of which abuts against a piston *e*, while its rear abuts 40 against a collar *e'*, screwed into the rear end of the tube *c*. Another piston *f* is fitted to slide in the rear part of the casing *b*, which has a longitudinal slot *b'* in its inner side, through which passes a pin *g*, projecting from 45 the piston *f* in rear of a stud *g'*, (indicated by dotted lines, Figs. 1 and 4,) which projects laterally from the side of the breech part *h* of the gun.

On the lower side of the casing *b* is pivoted 50 at *i* a trigger-lever, the front end *j* of which

forms a stop to the end of the tube *c*, while a pin *k* on its rear end is engaged in a cam-path *l*, formed on the boss of the breech-plug carrier *m*, which in opening or closing the breech turns on a vertical hinge. Through 55 a slot of the trigger-lever *j* *k* passes a spring-latch *n*, having its upper part tubular, with a notch to receive a hook *o*.

The front end of the tube *c* has attached to it a rope *p*, which passes over suitable guide-pulleys to the rounded top of an arm *q* on a rocking shaft *r*, which is mounted in a framing *q'* at the side of the breech of the gun. From the rocking shaft *r* a pair of arms *s* descend and carry a tray *t*, having its side connected by a pair of links *u* to projections *v*. Another rocking shaft *w*, on which is a spring *w'*, Fig. 2^a, urging it to turn in the direction of the arrow, Fig. 2, has one arm *w'*, which rests on one arm of a bell-crank lever *x*, the 70 other arm of which bears against one of the arms *s*, while *w* has another arm *w*², that acts as a stop to a projectile *y*, lying on an inclined charge platform or way *q'*, leading down to the tray *t*.

The apparatus operates as follows: When the gun recoils, the stud on it, acting on the pin of the piston *f*, drives that piston back and with it the piston *e*, which is rigidly connected to the piston *f* by a rod *f'*. As the 80 tube *c* is prevented by the nose *j* from moving rearward, the spring *d* is compressed, and a notch on the piston *f* is caught by the spring-latch *n*, so that the spring *d* remains in compression when the gun is advanced again to 85 firing position. At this time the arms *s* and tray *t* are in the position shown in Fig. 2, a projectile *z* being in the tray, and other projectiles, such as *y*, being held back on the incline leading to the tray by the arms of the 90 rock-shaft *w*. Now, on turning the plug-carrier *m*, opening the breech of the gun, the cam-path on its boss, acting on *k*, raises it, depressing the nose *j*, and thus releasing the tube *c*, which is impelled backward by the 95 spring *d* pulling the rope *p*. By the pull of the rope the arms *q* *s*, tray *t*, and links *u* are caused to take the position shown in Fig. 3, the projectile *z* being raised into position for loading in line with the bore of the gun. Also, the 10

bell-crank lever x being allowed to turn till it meets a stop x' on the framing q' , the arms of w are turned by the spring to an altitude which allows the projectile y to advance and bear against the arm of x . After the projectile z is loaded into the gun the breech is closed, and thus the latch n is drawn down, releasing the piston f , which was in its rear position, the end of the tube c abutting against it. The piston f and tube c being thus left free to advance, the arms s and tray t descend to the position shown in Fig. 2, pulling the rope p , by which the tube c , with the spring and pistons e and f , are brought forward to the position occupied by them before the gun recoiled. Also the lever x is turned by the arm s to such a position that the projectile y , that had been stopped by it, rolls down into the tray t , the succeeding projectile being stopped by the arm w^3 of w .

Obviously, instead of projectiles charges of explosive in cylindrical form might be raised by the apparatus, or by extending the tray t in length rearward such charges placed in the tray behind the projectiles might be raised along with them.

Having thus particularly described and ascertained the nature of this invention and in what manner the same is to be performed, we claim—

1. The combination with a breech-loading gun, of a charge-raising apparatus comprising a spring compressed by the recoil of the gun, a holder for the spring, a rope attached at one end to the spring-holder, a trigger-lever mounted on a non-recoiling part of the gun, to engage the spring-holder, a system of levers connected with the other end of the rope, a charge-raising tray carried by said system of levers, and a breech-plug carrier having a cam-path to move the trigger-lever and release the spring-holder, substantially as described.

2. The combination with a breech-loading gun, of a charge-raising apparatus, consisting of a spring, a stud on the breech for compressing the spring by the recoil, a spring-holder, a rope connected at one end with the spring-holder, a latch for detaining the spring when compressed, a trigger-lever mounted on a non-recoiling part of the gun and constructed to engage said latch and the spring-holder, a system of levers arranged at the gun-breech and connected with the other end of said rope, a charge-raising tray carried by said system of levers, and a breech-plug carrier having a cam-path for actuating said trigger-lever to release the spring-holder and retract the latch, substantially as described.

3. The combination with a breech-loading gun, of a charge platform or way and a supporting-framing near the breech of the gun, tray-carrying arms pivotally mounted on the framing, a charge-raising tray on the arms, mechanism for swinging the arms to raise and lower the tray, a two-armed lever on the framing, for stopping and releasing successive gun-charges, a transverse spring-turned shaft having two arms, one for tipping the two-armed lever and the other for arresting and releasing a gun-charge, and a stop for the two-armed lever when tipped by one arm of the spring-turned shaft, said tray-carrying arms acting, when lowered, to restore the two-armed lever and the spring-turned shaft to normal position, substantially as described.

In testimony whereof we have hereunto set our hands in presence of two subscribing witnesses.

ARTHUR TREVOR DAWSON.
GEORGE THOMAS BUCKHAM.
